OF D 14,009

Design No. 14,009, dated June 26, 1883.

UNITED STATES PATENT OFFICE.

EARNEST G. NUFFER, OF PHILADELPHIA, PENNSYLVANIA, ASSIGNOR TO GEORGE BROOKS & SON, OF SAME PLACE.

DESIGN FOR TAPESTRY OR DAMASK.

SPECIFICATION forming part of Design No. 14,009, dated June 26, 1883.

Application filed May 9, 1883. Term of patent 3½ years.

To all whom it may concern:

Be it known that I, EARNEST GARIBALDI NUFFER, a subject of the Emperor of Germany, residing in Philadelphia, in the county 5 of Philadelphia and State of Pennsylvania, have invented and produced a new and original Design for a Pattern to be Inwrought in Two-Ply Upholstery, Tapestry, or Damask, woven with two warps and two wefts, in such 10 shades or shades of materials as may be desired; and I do hereby declare that the photographic print accompanying this specification conveys to any one skilled in the art of weaving upholstery, tapestry, and damask a clear understanding of the same, and is sufficient to enable such persons to use my invention. 15

What I claim as my invention, and desire to secure by Letters Patent, is—

The design for upholstery, tapestry, or damask, as shown in the photographic print accompanying this specification. 20

EARNEST G. NUFFER.
